UNITED STATES PATENT OFFICE.

EDWARD C. HEGELER, OF LASALLE, ILLINOIS.

ZINC-SMELTING FURNACE.

SPECIFICATION forming part of Letters Patent No. 794,799, dated July 18, 1905.

Application filed February 2, 1903. Serial No. 141,520.

To all whom it may concern:

Be it known that I, EDWARD C. HEGELER, of Lasalle, in the county of Lasalle, in the State of Illinois, have invented certain new and useful Improvements in Zinc-Smelting Furnaces, of which the following is a specification.

The invention relates to that class of Belgian zinc-smelting furnaces in which the retorts are arranged in a horizontal flue or chamber of great length. In this class of smelting-furnaces the gases (including air) are introduced at the entrance end and along the course of the chamber. A pressure above atmospheric pressure and nearly uniform throughout the whole length of the retort-chamber is desired and movement of the gases through the chamber is required in the working of the furnace. Resistance to the movement of the gases increases with the length of the chamber, so as to require (suction in the chamber being injurious) a pressure so great in the chamber near the entrance end as to be detrimental there, and also the greater this pressure becomes the more difficult and expensive it is to produce.

The furnace construction considered in this specification relates entirely to the long flue-like chamber concerning which, as stated in former United States Patent No. 220,831, it was a separate part of that invention to arrange the long flue-like chamber horizontally. The specification of said patent states that the comparatively greater velocity of the gases in the direction of the flue's axis (caused by its narrow interior profile when compared to its great length) will cause them to pass along in the flue-like chamber when arranged horizontally nearly as rapidly at its bottom as at its top side, and experience in the use of the furnace constructed as shown in said patent, Figures 2, 5, and 8^a, proved that the upper tier of retorts were heated somewhat too hot. Relief from this was sought and obtained by contracting the space in the flue above the upper tier of retorts by lowering the rear of the top arch down to a little below the upper line of the top tier of retorts at their rear end, (making recesses in the arch for them.) Such method of reducing the heat of the upper retorts carries with it an

increase of the resistance to the passage of the fire-gases through the flue-like horizontal chamber. Other changes in the construction of the furnace from the design of said patent of 1879 had previously been made, viz: First, 55 the perforated retorts to serve for the introduction of air into the retort-chamber and placed between the retorts charged with ore were omitted, thereby creating open vertical spaces between the several sections of four- 60 ore retorts each, and, second, the floor below the bottom tier of retorts of the long flue-like chamber was lowered to give space for droppings from the retorts above; but dams of sand were made on the floor at every section 65 of four retorts of a height sufficient to project a little into the vertical spaces between the sections of retorts to obstruct the draft. These spaces below may have helped some toward the heating of the lower tiers of re- 70 torts more uniformly with the upper ones. It was also found that in a furnace consisting of eighteen sections of four retorts each horizontally and six rows high the sand dams could be omitted under the first seven sec- 75 tions without showing bad effects on the uniformity of the heating. The resistance to the movement of the gases in the long flue-like horizontal chamber from entrance to exit was somewhat reduced thereby, and this and the 80 easier cleaning of the bottom and the saving of the work of making the dams were advantages.

The first object of the present improvements is to provide means for reducing the 85 resistance to the moving gases in the long flue-like horizontal retort-chamber without injuring but rather facilitating the uniform heating of all the retorts in securing a greater mixing of the gases in the upper and lower 90 parts of the retort-chamber, maintaining the uniformity of the gases while passing through the chamber, and also facilitating the cleaning of the bottom of the chamber, as herein-after specified; and the present invention con- 95 sists principally in the discovery of the possibility of utilizing increase of open space under the roof of such a chamber for reducing the resistance to the movement of the gases through the chamber without interfering 100

with but improving the uniformity of the heating of the retorts by having said open space in recesses in conjunction with open space or spaces in such chamber under the 5 lowermost tier of retorts. I attain these results by providing the bottom and top of the retort-chamber with a series of recesses above and below the retorts, which recesses I prefer to have staggered in the bottom and top rather 10 than arranged opposite to one another, as the staggered form gives the better results.

Another object is to give greater uniformity of the gases in the retort-chamber near 15 the entrance, and another object is to increase the heat near the working front of the retort-chamber and reduce it at the rear wall, on which the rear ends of the retorts are supported.

The invention is illustrated in the accompanying drawings, showing a furnace comprising two retort-chambers arranged side by side, by which these objects are obtained.

Fig. 1 is a vertical longitudinal section of a central fragment of a retort-chamber embodying the first part of my invention and showing the retorts arranged therein. Fig. 2 is a sectional plan view of a furnace constructed for the use of generator-gases with the improvements applied, showing a fragment of that end of the retort-chambers where the gases are introduced in connection with a fragment of the induction-flue on the line 11 of Fig. 3. Figs. 3, 4, and 5 show fragments of a vertical longitudinal section of one of the 35 chambers, taken at the line 22 of Fig. 2. In these views, Fig. 3 shows the front part with a fragment of the gas-induction flue whereby the gases enter. Fig. 4 shows the central part, and Fig. 5 the rear part, at the exit of 40 the retort-chamber with a fragment of the exit-flue. Fig. 6 is an enlarged fragmentary transverse section of the chamber, taken on the line 66 of Fig. 3. Fig. 7 is an enlarged fragmentary transverse section of the 45 chamber on the line 77 of Fig. 3. Fig. 8 is a detail showing an enlarged horizontal section in fragment through the front wall of the chamber at the plane of one of the air-inlets. Fig. 9 is a detail showing a vertical section on the line 99 of Fig. 8. Fig. 10 is a detail showing a fragment of a front elevation of the means for closing the air-pipes before the air-inlets. Fig. 11 is a detail showing a perspective view of a slotted stopper 55 for the air-inlets. Fig. 12 is a detail showing one of the air-inlet tubes. Fig. 13 is a detail showing a modification.

In the drawings, A designates long horizontal retort-chambers arranged on opposite 60 sides of a central wall A', and B the retorts therein, with rear ends resting on steps B' of the central wall.

The distance of the retorts apart in the horizontal rows is ordinarily about two inches,

more or less, except at intervals where they 65 are preferably placed farther apart to form greater spaces before the air-inlets, as shown at a a, so as to form groups of retorts intermediate the said spaces at a a. The uppermost row of retorts is near the top or roof of 70 the chambers in every alternate section or group of retorts, but not in the sections between them, and the lowermost row is considerably above the bottom or floor, with a sand dam on the floor under every alternate 75 section of the retorts.

The top or roof of each of the chambers is formed of a succession of high sections or arches C and low sections or arches C' on each side of the central wall arranged alternately 80 throughout the entire length of the chambers, the high sections forming a series of recesses 1, in which no retorts are placed, and the bottom or floor of each chamber is level or flat except at points under the high arches, where 85 it is provided with dams or ridges C², best formed of sand piled up on the floor, so that the apex of the pile shall come just a little below the under side of the lowermost row of retorts. The flat bottom thus provided with 90 the ridges running transversely of the chamber forms a series of recesses 2, in which also no retorts are placed.

Figs. 3, 4, and 5 show the relative arrangement of the arches, the ridges, the recesses, 95 and the retorts arranged in groups, the upper and lower recesses each being connected by the air-inlet spaces between the groups of retorts. The low arches C' are arranged transversely of the chambers and abut against 100 the upper end of the central wall A' at the rear and against a V-shaped iron casting at the top of the front wall A², so as to approach the upper surfaces of the uppermost row of retorts, and the high arches C are extended 105 longitudinally of the chambers over the spaces between the transverse arches and have their ends abutting against and supported by the opposite edges of the arches, as shown at c, except at the starting-points at the ends of 110 the chambers. Said transverse arches thus unite with the central and front walls of the chambers approximately at the same level and, with the high arches, form a continuous roof or top along the entire length of both 115 chambers.

By the construction of the roof and bottom of the long horizontal chamber so as to form staggered recesses therein and improved by the arrangement of the retorts in the chamber within the space outside of and between said upper and lower recesses the cross-sectional area of the passage-way for the gases through the chamber is increased over that of furnaces of this class as heretofore constructed, and thereby the resistance to the movement of the gases through the chamber is reduced and the increased space is so dis-

posed relatively to the retorts as to secure the better mixing of the gases in their movement through the chamber.

In operation the gases move unobstructed 5 horizontally through the space between the retorts with a slight movement upward as they approach the recesses in the roof and a slight movement downward as they approach the recesses in the bottom of the chamber. In 10 the vertical spaces between the groups of retorts, if there be such, an upward or downward movement takes place besides the horizontal movement. The spaces between the ridges on the bottom of the chamber become 15 larger than heretofore, when there were ridges under every section of retorts, by leaving out every alternate ridge, and the molten dropings from the retorts and interior of the chamber can be more easily broken up and 20 removed than in the old construction.

The arched roof may be so made that it will settle with the settling of the central wall, from shrinkage of the wall, without impairing the arch structure or support of the roof. 25 With this end in view the inner or rear ends of the low transverse arches C' are made to abut against the wall A' for the space of about one-fourth their thickness only, as shown at c', Fig. 7, the upper part projecting above the 30 upper line of the said wall, an open space being left at c² above said wall and between the upper part of the ends of opposite arches C', which span the chambers on opposite sides of the central wall. This open space is covered 35 by long bricks c³, laid loosely upon the adjacent ends of the transverse arches over said intervening space. When the wall A' shrinks or settles down under the effect of the heat of the furnace, the inner ends of said low arches 40 and their connection with the said wall can yield, without breaking, sufficient to let said arches go down with the central wall without material injury to the roof structure. The wall A' at the points between the high longitudinal arches C is constructed higher, as 45 shown at D, Fig. 6, but should not come up to the under surface of these arches. The inner edges of these arches, as shown at c⁴, approach each other, when the central wall A' settles. The open space between the wall A' 50 and the lower edges of the high arches is covered by bricks c⁵, resting on the central wall and leaning against the edges of the said longitudinal arches. An outer covering of long 55 bricks c⁶ is provided to close over the space between the inner edges of the adjacent high or longitudinal arches C.

The rear end of the chamber where the 60 burned gases pass out is provided with an exit d' at about the level of the top, and the last ridge C² is placed under the last transverse arch C' and extended to the end wall a², which directs the gases up to the exit. They pass thence through a flue b to an air-heater (not

shown) or may be allowed to escape through 65 the opening b', provided with a slide-valve b².

In smelting-furnaces of the class mentioned as heretofore constructed the generator-gases are mixed with sufficient air to heat them to the temperature required at the first retorts 70 through air-inlet openings in the outer side walls of the entrance of the chamber just before the first retorts. The size of these air-inlet openings is made and regulated with great care by slight enlargement or reduction 75 of size to obtain the right degree of heat and also a uniform heat of the first section of retorts. The quantity of air that has to be let into the generator-gases before their contact with the first retorts is a large part of the air 80 required for their complete combustion, and the thorough mixing of it with the generator-gases necessary for a uniform heating of the first retorts is difficult, and local injury to the retorts and walls from heat results, as also inequality in the working of the two retort-chambers. In the endeavor to overcome this 85 difficulty I have let air into the sides of the gas-flue leading from the producer to the retort-chamber, but did not obtain any satisfactory results. My improvement now consists in the introduction of mixing devices, together with the air-inlet openings in the walls 90 of the gas-flue. I make these air-inlet openings of such dimensions that they will admit 95 into the gas-flue nearly all the air that has to be brought to the gas before its contact with the retorts, and I connect a valve with these openings by which I regulate the somewhat varying quantity of necessary air resulting 100 from the inequalities of the producer-gas. As the mixing devices hereinafter described would be injured by heat notwithstanding 105 their solid construction if the whole air (required before the first retorts) should be let 110 in at the new place, I retain the air-inlet openings at the entrance to the retort-chambers, but reduce their dimensions until I notice injury to the gas-flue, when I slightly enlarge them again.

The mixing devices which I have employed and which are illustrated in Figs. 2 and 3 of the drawings are twofold. First, I have the generator-gases as they come through the flue or its by-passage E' (provided with a valve e) 115 pass through a contracted portion e' e' of said flue, in the opposite sides of which large air-inlet openings e² e² are provided and distributed over the sides, as shown in Fig. 3, through 120 which air is introduced into said contracted portion; second, from this contracted portion of the flue, which is horizontal, I have the generator-gases in a sudden break, causing a whirl, pass into an enlarged vertical portion E² of the flue in which they descend and from 125 the lower part of which the thoroughly-mixed gases pass through entrance-openings e² e² to the retort-chambers, receiving additional air

through smaller air-inlet openings e^4 , placed just before the first retorts. The horizontal part of the flue is preferably slightly further contracted for a short distance at e^5 . The gases passing through the horizontal part receive air introduced at $e^2 e^2$ from opposite sides of the flue and thence pass into the vertical part with a whirl and are thoroughly mixed throughout their entire volume with the air so introduced before passing into the entrance-openings of the retort-chambers. The entrance-openings $e^3 e^3$ into the chambers consist in arched passages through the thick wall A^3 of the retort-chamber and are inclined toward the working front sides of the chambers, the outer sides of said passages being about in line with the interior of the front walls A^2 of the chambers. The end wall A^3 is constructed on a curve, as seen in Fig. 2, with the convex side joined firmly to the end of the central wall A' as integral therewith, so as to cover and protect the end of said central wall, while the concave part forms one side of the vertical part of the gas-flue.

The ordinary means for supplying and regulating the inlet of air to the chambers consists of a series of air-pipes F , which are connected with mains F' overhead and communicate with a source of hot-air supply under pressure. The air-pipes F are arranged opposite to the spaces $a a$ between the retorts and are provided with openings in their inner side, having flanges f and similar openings in their outer side, provided with a vertically-sliding door f' , Figs. 8 to 11, said openings being in line. The door has projecting lugs, adapted to slide down behind inclined ears 4 of the pipe F to hold the door over the opening in the outer side. The flanges f are pressed into the plastic fire-clay structure f^2 of the front wall in the process of erection and while it is wet. Then a hole f^3 is bored through the said plastic structure corresponding in diameter of bore with the interior of the flange f . This bored hole f^3 (after the clay is dry) is filled with soft fire-clay f^4 and then at the site of hole g^3 , Fig. 13, a hole is made through it with a bar of such cross-section as the hole is to have. The size of this hole at g^3 is the ordinary means for regulating the quantity of air admitted at this place, and the air comes out of the hole in a jet, striking the wall A' . Now instead of filling the bored hole f^3 with soft fire-clay and making a hole through it with a bar, as described, I insert into hole f^3 a short burnt fire-clay tube G , closed at one end g and having an opening g' in the side near said end, so that its end with the opening g' will project a short distance from the front wall into the retort-chamber.

In the specification of the former Patent No. 220,831 there are described large air-retorts the same as the ore-retorts and supported at both ends on the rear and front walls and provided with perforations along their whole

length for letting air from the retort into the chamber. The short burnt fire-clay tube G here described is such a retort, except being in miniature and having openings near the closed end only and bringing air into the chamber near the front wall only and supported at its open end only by being there embedded in the front wall.

The opening g' is large, so as not to make a jet of air, but diffuse it near the front wall, and does not regulate the quantity of air admitted. The fire-clay tube G after insertion into the hole f^3 is made tight therein with fire-clay. The regulation of the quantity of air to be admitted through tube G is done by the size of the slotted opening g^2 , cut into a new sheet-iron stopper G' , which stopper is inserted into the inner flange f at its junction with the pipe F , which has been reamed for the purpose of making a close fit with the stopper. This removable stopper G' , with the regulating-opening g^2 , can also be used to advantage in connection with a hole g^3 made through a filling of soft fire-clay f^4 inside of hole f^3 , the hole g^3 being made larger than the hole at this place, as ordinarily used to regulate the quantity of air let into the chamber. The filling f^4 then serves for making a hole g^3 into the chamber of less diameter than the hole f^3 , so as to prevent the chamber-gases from circulating into said hole f^3 . It further serves for making said hole g^3 either smaller or larger within the area of said hole f^3 for giving more or less jet to the air entering the chamber through said holes g^3 . The advantage consists in saving the attention, care, and labor required for keeping the holes now at g^3 in perfect order, they being the regulating-holes, as is well known.

Having thus fully described my invention, what I claim, and desire to secure by Letters Patent, is—

1. In a zinc-smelting furnace of the class specified a long, horizontal retort-chamber through which the gases pass unobstructed, except by the retorts, in the direction of its greatest extension and having a roof provided with a series of recesses, and a bottom provided with a series of recesses, in combination with the retorts arranged between the roof and bottom, in the space outside the recesses, substantially as specified.

2. In a zinc-smelting furnace of the class specified a long, horizontal retort-chamber through which the gases pass unobstructed, except by the retorts, in the direction of its greatest extension and having a roof provided with a series of recesses, and a bottom provided with a series of recesses, the recesses of the roof and bottom being staggered, in combination with the retorts arranged between the roof and bottom, in the space outside the recesses, substantially as specified.

3. In a zinc-smelting furnace of the class specified a long, horizontal retort-chamber

through which the gases pass unobstructed, except by the retorts, in the direction of its greatest extension having staggered recesses in its roof and its bottom and in combination with the retorts arranged in the space outside the recesses and separated into groups by open vertical spaces, the recesses in the roof and bottom being arranged alternately over and under the space occupied by a group of retorts and the pair of open vertical spaces adjacent thereto as specified.

4. In a zinc-smelting furnace of the class specified the long, horizontal retort-chamber provided with air-inlet openings at its entrance, the gas-flue leading to the chamber provided at a point some distance from the chamber with air-inlet openings, and mixing devices in the flue, located between the air-inlet opening thereof and the air-inlet openings at the chamber-entrance, as specified.

5. In a zinc-smelting furnace of the class specified having air-inlet pipes F, provided with inside openings at f, the removable sheet-iron slotted stopper G' for said openings, substantially as specified.

25

6. In a zinc-smelting furnace of the class described, the long horizontal chamber provided with vertical rows of openings in the front wall at intervals, vertical air-pipes provided with coincident openings in their inner and outer sides registering with said openings in the front wall, and air-inlet pipes shorter than the chamber's width, provided with closed inner ends and side openings, and extending from the openings in the front wall into such chamber, as specified.
